UNITED STATES PATENT OFFICE.

FRANK W. BEARDSLEY, OF NEW YORK, N. Y.

SASH-FASTENER.

1,116,213.

Specification of Letters Patent.

Patented Nov. 3, 1914.

Application filed January 9, 1913. Serial No. 740,911.

To all whom it may concern:

Be it known that I, FRANK W. BEARDSLEY, a citizen of the United States, and a resident of New York, Dongan Hills, Richmond borough, in the county of Richmond and State of New York, have invented certain new and useful Improvements in Sash-Fasteners, which improvements are fully set forth in the following specification.

10 This invention relates to improvements in devices of that class quite extensively used at the meeting rails of, and for interlocking purposes in connection with, the customary upper and lower sash of a window, such devices being commonly known as sash fasteners.

The object of this invention is to provide a sash fastener of the type above indicated, which shall be simple and comparatively inexpensive as regards construction; durable, and of marked efficiency in practical service; self-acting for a locking effect between said upper and lower sash, upon the latter being duly adjusted, each relatively to the other; which shall embody features of construction permitting manipulation of its operating parts, particularly for an unlocking effect, at the inner face only of the sash in conjunction with which it is used; and which shall possess certain well-defined advantages over prior analogous devices.

The invention consists in the combinations, details and parts whereby, together with the novel disposition and relative arrangement of said parts, the attainment of the foregoing object is rendered practicable, all of which will be hereinafter more specifically referred to and set forth in the appended claims.

40 The invention is clearly illustrated in the accompanying drawings, wherein similar reference-numerals denote like parts throughout the respective views, as to which:

Figure 1 is a plan view of a sash-fastener embodying my said improvements, the same being shown as generally applied to the meeting rails of the upper and lower sash of a window. Fig. 2 is a view similar to Fig. 1, showing the device detached from the sash-rails aforesigned, the crown of the main casing being removed and a portion of the crown of the keeper being broken away. Fig. 3 is an enlarged detail view, wherein

the main casing is shown in elevation with a portion of the side-wall and crown thereof broken away, and the keeper aforesigned is shown in central, transverse section. Fig. 4 is an enlarged detail view showing, independently of the main casing and in side-elevation, the general trip-mechanism which I purpose making use of, the same being reversed endwise from the position it is shown as occupying in Fig. 3. Fig. 5 is an enlarged detail sectional view of certain parts or elements located centrally of the device and involved in the control and operation of the locking-button which I make use of. Fig. 6 is a detail perspective view of said locking-button, detached.

Having reference to the accompanying drawings forming a part hereof, I purpose, in carrying out my invention, to make use of an inverted, box-like, main casing 2, disposed on the meeting-rail, as 2' of the lower sash, and held in position as by means of the screws 2" 2"'; and a keeper 3, disposed on the meeting-rail, as 3', of the upper sash, in registry with the main casing 2, and held in position as by means of screws 3" 3'''.

4 is a vertical, rotatable pintle, arranged centrally of the casing 2, and having a suitable bearing, as at the point 4'.

4" is a cap and 4"" a locking-button, fixed, respectively, on the pintle 4 at the upper and lower portions thereof, said cap being provided with a finger-piece 5, and said locking-button having a marginal riser *a*, arranged eccentrically to the pintle 4 and gradually diminishing in height from the heel to the tip thereof.

In the main, the keeper 3 is of an inverted, box-like form, and is provided with an interior lug or tongue 5' which depends from the crown thereof.

The button 4"" is controlled by an elastic element, preferably in the form of a volute spring 5", fixedly attached at one end, as at the point 5'', and attached at its opposite end, say to the pintle 4, the tendency of this element being, at all times, to elastically urge the button 4"" into its locking position, where the riser *a* takes more or less around and engages the lug 5', beneath the crown of the keeper aforesigned, thereby not only transfixing the upper and lower sash to which the device may be applied,

and in such a manner that the one may not be lowered nor the other raised, independently, but, by reason of the eccentric form aforesaid of said riser, tending to draw 5 said upper and lower sash snugly together, at the meeting-rails thereof, all as clearly indicated in Fig. 2 of the drawings.

I am aware that the construction thus far described is essentially old and well known 10 in the art; also that trip-mechanism purporting to hold the locking-button of a sash-fastener out of its locking position, and, through proper lowering of the lower sash relatively to the upper sash, automatically 15 release said button for a return movement into its locking position, has been heretofore availed of; but in this latter connection it is not rarely necessary, as a condition precedent to the setting or adjustment of 20 any such trip-mechanism for a restraining effect on said button, that the lower sash be first somewhat raised relatively to the upper sash. This is objectionable, for the reason that, in practice, the user of such a fastener 25 is required to hold, with one hand, the locking-button thereof out of its locking position, and at the same time attempt, with the other hand, to raise said lower sash, an operation frequently attended with much 30 difficulty.

I overcome the above-named objectionable feature of prior analogous devices by employing, as a leading characteristic of my improved sash-fastener, and for coöperation with the locking-button thereof, a constant-set trip-mechanism, by preference comprising substantially the parts and details which will now be described:

6 is a trip-lever working on the pivot 6', 40 having a downwardly-turned tip 6'', and provided with an upstanding dog 6''', the latter disposed to rock to and fro, as on the pivot 7. Said trip-lever is suitably recessed, as at 7', to measurably receive the dog 6''', 45 substantially as shown in Figs. 2 and 4, said dog having a flat bottom-surface against which normally impinges the free end-portion of the leaf-spring 7'', attached to the trip-lever 6 at its under edge, and as at the 50 point 7''', said spring tending at all times, accordingly, to elastically hold the dog 6''' in a vertical position.

A supporting-arm 8, formed integral with, or otherwise fixedly disposed relatively to the main casing 2, interiorly thereof, overlies the trip-lever 6 and serves to limit the upward movement thereof.

8' is a catch-lever, pivotally attached to the arm 8, at its free end. Said catch-lever 60 is provided, at its advance end, with a catch 8'', which coöperates with the notch 9, here shown as formed in the bottom of the locking-button 4''', said catch being held yieldingly to a sliding engagement with the bottom surface of said locking-button by means

of a leaf-spring 9', whose free end, for this purpose, bears upwardly against the advance end of said catch-lever. The opposite end of the catch-lever 8' suitably overlies the dog 6'''. 70

It will now be observed that the locking-button aforesaid, the same having been duly swung against the tendency of its controlling spring, will be held against a return movement thereof in response to its controlling spring, by reason of catch 8'' entering the notch 9 and engaging the upright wall thereof, as indicated in Fig. 3; and this irrespective of whether the free end-portion of the trip-lever 6 be elevated or depressed. 80 When depressed, however, as will follow the suitable lifting of the lower sash of a window to which my improved fastener may be applied, the dog 6''' will automatically right itself, so that its upper free end will stand under the adjacent, overlying end of the catch-lever 8'. Now, upon said lower sash being lowered, as to bring the top surface of its meeting-rail into registry with the top surface of the meeting-rail of said 90 upper sash, the down-turned tip of the trip-lever 6 engages the top surface of the meeting-rail of said upper sash,—the crown of the keeper aforesaid being cut away, as at 9'', to provide clearance for the trip-lever 6, accordingly,—and as said lower sash continues its movement downwardly, the free end of said trip-lever moves upwardly, with respect to the top surface of the meeting-rail of said lower sash, taking 100 with it the dog 6''', which, accordingly, trips momentarily the catch-lever 8', sufficiently and in a manner to disengage its catch 8'' from the notch 9, thereby releasing the locking-button 4'''; said dog, immediately thereafter, rocking out of its engagement with the adjacent end of said catch-lever, thereby releasing the latter, and permitting the same, under the action of its controlling spring, 9', to automatically reset 110 itself for a further locking engagement with the locking-button 4''', upon the latter being again duly moved against the tendency of its controlling spring,—this, even though the trip-lever 6 occupies its elevated position, and even without lifting said lower sash. Upon the latter, however, being again duly lifted, trip-lever 6, either by its own gravity, or under the impulse of the spring 115 9', the latter, in this instance, being secured to said trip-lever, as at the point 8''', moves downwardly; dog 6''' again rights itself, beneath the adjacent end of the catch-lever 8', and upon said lower sash being again duly lowered, the foregoing operation is 120 repeated.

The main casing 2 is provided with a socket 9''', which depends centrally therefrom, is open at its top, to permit the adjustment therein accordingly of the spring 130

5", and the pintle 4 bears in the bottom wall of said socket, as at the point 4', while the cap 4" controls the mouth thereof.

It is to be understood that under release-
5 ment of the locking-button aforesaid as
above defined, the same moves automatically
into a locking engagement with the
keeper aforesaid, and particularly the
tongue 5' thereof, as clearly indicated in
10 Fig. 2 of the drawing.

It will be seen that my improved sash
fastener is well adapted for the purposes
for which it is intended, and further that
the same may be modified to a considerable
15 extent, particularly as regards the specific
elements made use of whereby the restraining
of the locking-button aforesaid against
the action of its controlling spring is effected
without the necessity of first lifting the lower
20 sash, and as frequently prevails in prior
analogous devices, all without departure
materially from the scope of the appended
claims.

I claim:

25 1. A sash fastener comprising a casing
having a swinging locking-button; a keeper
engageable by said locking-button; a spring
tending normally to urge the locking-button
aforesaid into locking engagement with
30 said keeper, said casing and keeper being
duly mounted, respectively, on the meeting-
rails of the lower and upper sash of a win-
dow; a spring-controlled catch-lever adapt-
ed to lockingly engage, automatically, said
35 locking-button, and temporarily hold the
same retracted against the tendency of its
controlling spring, said catch-lever pivot-
ally disposed independently of said locking-
button, within the casing aforesaid; and
40 a trip-lever, the latter pivotally disposed
within said casing beneath the catch-lever
aforesaid, projecting from said casing into
the plane of, and overlying, the meeting-
rail of the opposite sash, and supporting in
45 registry with the catch-lever thereabove an
upstanding dog, the latter being adapted,
accordingly, to engage, trip and release said
catch-lever.

2. A sash-fastener comprising a casing

having a swinging locking-button provided 50
with a notch; a keeper engageable by said
locking-button; a spring tending normally
to urge said locking-button into locking en-
gagement with said keeper, said casing and
keeper being duly mounted, respectively, on 55
the meeting-rails of the lower and upper
sash of a window; a spring-controlled
catch-lever, adapted to lockingly engage,
automatically, said locking-button at the
notch thereof, and temporarily hold the 60
same retracted against the tendency of its
controlling-spring, said catch-lever pivot-
ally disposed independently of said locking-
button, within the casing aforesaid; and
a trip-lever, the latter pivotally disposed 65
within said casing, projecting somewhat
therefrom into the plane of the meeting-
rail of the opposite sash, overlying the lat-
ter and underlying said catch-lever, and
having pivotally attached thereto a spring- 70
controlled dog, said dog adapted, upon the
free end of said trip-lever being elevated,
to engage, trip and release said catch-lever,
whereby said locking-button is freed to au-
tomatically respond to the impulse of its 75
controlling-spring.

3. A sash-fastener comprising a casing
having a socket depending centrally therein
from the crown thereof, said socket formed
integral with said casing, and access to 80
whose interior is essentially had only at
the open-top thereof; a pintle disposed to
rotate axially within said socket, said pintle
projecting downwardly through, somewhat
beyond, and bearing in the bottom wall 85
thereof; a spring let into said socket from
the top thereof, and encircling and con-
trolling said pintle; a locking-button fast
on said pintle, at its lower end, beneath
said socket; and a cap, the latter fast on, 90
and affording an additional bearing for,
said pintle, at its upper portion, overlying
and closing the open top of said socket, and
provided with a finger-piece.
